Specification of Letters Patent.

Patented Dec. 26, 1916.

Application filed June 15, 1915, Serial No. 34,227. Renewed May 27, 1916. Serial No. 100,360.

To all whom it may concern:

Be it known that I, WILLIAM MORTON JAMES, a subject of the King of Great Britain and Ireland, and residing at Manchester, in the county of Lancaster, England, have invented new and useful Improvements in Aeroplanes, of which the following is a specification.

This invention relates to improvements in aeroplanes, the objects of which improvements are to obtain greater longitudinal stability, simpler and more efficient elevation control and reduced resistance from the elevation control planes.

In my improved machine, the control planes which are in the form of separate wings constitute part of the supporting area, the main portion of the supporting area being fixed while the control planes are movable. The supporting planes or wings comprising the main fixed planes and the control planes are arranged in pairs in series longitudinally, the minimum number of such pairs being three, of which the extreme fore and aft pairs are elevation control planes. These elevation control planes are made angularly adjustable, being hinged to the body or fuselage longerons on each side with the axes thereof longitudinal. The control planes are set with a normal positive dihedral angle in a machine with three pairs of planes, of preferably 15°, but this may be increased up to 25°, and their controlling connections and gear are such that the dihedral angles of the fore and aft pairs, can be simultaneously varied in opposite directions, that is to say, if the angles of the fore pair or pairs are increased, those of the after pair or pairs are simultaneously decreased, the limit of downward movement being preferably the horizontal. The maximum lift of the extreme end control planes is double the normal, that is to say, if they are set with a normal dihedral angle of 15°, the maximum angle would be 30°; if the normal angle be 25°, the maximum angle would be 50°.

In the case of machines with more than one pair of main or fixed supporting planes or wings there would generally be more than one pair of fore and aft control planes and the inner pairs would preferably have a lesser normal dihedral angle and a lesser movement. There would always be a central pair of fixed planes or wings, and the

fixed supporting planes would always be in an equal number of pairs on each side, fore and aft of the central pair. The control planes would also be in pairs in even numbers fore and aft of the fixed planes. Each plane of each pair of control planes is balanced by the other, and the angles of all the pairs are adjusted in the manner required by means of a hand controlling device and cables in such a manner that those forward of the central fixed supporting plane or planes are elevated and those aft are depressed simultaneously, the degrees of variation being for extreme fore and aft pairs, equal, and for the next fore and aft pairs, equal, and so on. The central pair of planes or wings are preferably horizontal or in one plane. The other pairs of fixed planes when more than one pair are employed, that is to say, those next to the central plane or planes on each side, are fixed with a slight dihedral angle and this slightly increases with the number of pairs more than three. In any case, the dihedral angle of any of the planes intermediate of the two end pairs would not exceed the normal dihedral angles of these two pairs.

With this improved arrangement of control planes and controlling gear, the longitudinal extremities of the machine are simultaneously moved in opposite directions, that is to say, up and down, one end pair of control planes obtaining increased support on the air and the other end pair decreased support on the air. No increased resistance is offered by the control planes to forward motion. The system of connecting the control planes with the controlling device used, makes the fore pair or pairs balance the after pairs or pairs. Assuming the angles of the control planes have been altered from the normal and the control handle is released, the tendency will be for the control planes to assume their normal angle again.

The drawings attached hereunto illustrate two multiplane machines constructed in accordance with my invention.

Figure 1 represents a multiplane machine with three pairs of wings in side elevation; Fig. 2 the same in front end elevation and Fig. 3 the same in plan. Fig. 4 represents a plan of a machine with seven pairs of wings or planes and Fig. 5 a side elevation of the same. Fig. 6 is a cross section through the body and pylon at x , x , of Fig. 1, show-

ing the bracing arrangement of the controlling planes. Fig. 7 is a similar view showing the controlling cable arrangement at this part the bracing wires being omitted. Fig. 8 shows diagrammatically, the controlling lever and control cables in side elevation and Fig. 9 represents the control lever and mounting in elevation looking from behind. Fig. 10 is a cross section of the body and pylon at y, y' , of Fig. 5. Fig. 11 is an elevation of a hand controlling wheel.

Figs. 1 to 3 and 6 to 9 will first be referred to. The body represented by 1, is preferably of the form shown so as to offer the least possible resistance. It is mounted as usual on a chassis 2 which is provided in this machine with four wheels. The main supporting surface is provided by two wings 3 and 3' which lie in the same horizontal plane. These wings have the approved form in cross section, and have an angle of incidence of one in twenty. They are braced in the usual way by bracing wires 4 connected to a pylon 5 above and to the body below. The wings are practically central longitudinally of the body. The well 6 for the pilot is situated behind the transverse center, and the power plant, not indicated in the drawings, in advance thereof. Two tractor screws 7 and 7' are employed and these are in advance of the main supporting plane. The screws are driven preferably by chain gear. No ailerons are shown in this machine and no warping arrangements, but such may be applied in the usual way if desired. The rudder is represented by 8.

The elevation control planes are as stated, in pairs and hinged to the body, one pair forward and the other pair aft. The forward pair are represented by 9 and 9' and the after pair by 10 and 10'. They are pivotally secured preferably to the top longe-
45 rons (not shown) of the body at a and a' and in the drawing are set with a normal dihedral angle of 15° which is at present preferred, but the normal dihedral angle may be anything between say 10° and 25° . The movement of these control planes is regulated by the control lever and gear so that neither pair can be lowered below the horizontal plane or raised above the maximum dihedral angle which in the case of the machine illustrated is 30° with a normal dihedral angle of 15° . If the normal dihedral angle be 25° the maximum would be 50° . In cross section, the control planes have approximately the same camber and the same angle of incidence as have the main supporting planes. These control planes are cross braced to the body in such a manner that one plane of each pair cannot move up or down without the other moving in a corresponding degree. Also they are so connected through the controlling arrangement
60 that the forward pair shall move in the
65

opposite direction to the after pair, that is to say, the two pairs being at the normal dihedral angle of 15° , when the control lever is moved one way or the other past its neutral point at which the planes remain at the normal angle, one pair of planes move upward and the other downward.

The bracing cables are shown in the elevation views Figs. 1 and 2 and in the plan Fig. 3 and marked 11, 11' and 12, 12' in each pair of planes. Fig. 6 shows on an enlarged scale, more or less diagrammatically, the arrangement of bracing for assuring the synchronized movement of the two planes of each pair upward or downward. In this view the control planes are shown in the horizontal position. This view shows also the body and pylon in cross section on the transverse center line of the control planes 10 and 10'. The reference letters are the same for both forward and after control plane details. There are four bracing cables to each pair of control planes but only two are seen in Fig. 6. The cable 11 is connected to the upper side of the planes 9 and 9' or the planes 10 and 10' at 13, passes over a pulley 15 in the pylons p and p' , is carried downward and passed around another pulley 16 in the body 1 and then carried upward and connected at 17 to the under side of the plane 9' or the plane 10' at a distance from the fulcrum of the plane equal to that of the distance of the point 13 therefrom. The cable 12 is connected to the upper side of the plane 9' or the plane 10' at 13', passes upward over the pulley 15', downward to and around the pulley 16' and then upward to the point 17' under the plane 9 or the plane 10. The cables 11' and 12' are connected in an exactly similar manner, passing of course over separate pulleys.

Figs. 7, 8 and 9 show also on an enlarged scale, more or less diagrammatically, an arrangement for operating the two pairs of control planes simultaneously. Fig. 7 represents a cross sectional view through the body and pylon, similar to Fig. 6, representing the arrangement of the controlling cables from either pair of control planes into the body 1. Fig. 8 represents the control lever and the connections between the pylons p and p' , in side elevation. Fig. 9 represents a back end view of the control lever and mounting and shows the connections of the control cables thereto.

There are eight control cables for the two pairs of control planes, four upper ones and four lower ones, and these connect the two pairs of planes together. These cables are all connected to the control lever at one end and to the control planes at the other end, and when the controlling handle is moved, four cables move in one direction and four in the opposite direction whereby the cables being in pairs one pair above the other,

on each side of the control lever, the upper pair at each end being connected to the top sides of the pair of control planes at one end of the machine and the under pair at each end being connected to the underside of the same planes, when the controlling lever is moved forward, the fore pair of planes are lowered and the after pair are raised. The two upper cables from the 10 after pair of control planes are marked 20 and 21 and the two lower ones 22 and 23, and the two upper from the front pair of control planes, 20' and 21' and the two lower, 22' and 23'. The control cable 23' 15 is not seen in the drawings.

The control lever stem is represented by 24, see Fig. 9, and is shown with a circular handle 25 at the top end. It is fixed to a rocking shaft 26 journaled in end bearings 20 27. On the rocking shaft are fixed two pairs of diametrically opposite arms, the upper ones being marked 28 and 29 and the lower ones 28' and 29'. The mounting of the rocking shaft 26 is situated below the 25 foot board of the pilot in the well 6.

As Fig. 7 represents the after pair of control planes, the connections to these will be first referred to. Now the cable 20 is joined to the plane 10 on top at 20'', passes 30 over the pulley 30 in the pylon p' , around the pulley 31 in the body and is connected to the arm 28 of the rocking shaft 26. The cable 21 is joined to the plane 10' at 21'', passes over the pulley 30' in the pylon p' , 35 around the pulley 31' and is connected to the arm 29. The lower cable 22 is joined to the underside of the plane 10 at 20'', passes around a swiveling pulley 32 in the body and is connected to the arm 28'. The 40 cable 23 is joined to the plane 10' at 21'', passes over the swiveling pulley 33 in the body and is connected to the arm 29'. The upper cables 20' and 21' from the front pair of control planes 9 and 9' are connected in an exactly similar manner to said 45 planes and are guided around pulleys in the forward pylon p , corresponding to the pulleys 31 and 31', in the aft pylon p' and are finally carried down and connected to the arms 28 and 29 of the rocking shaft 26. The lower cables 22' and 23' from the forward pair of control planes are also connected in an exactly similar manner to said 50 planes and guided around swiveling pulleys in the body and are finally connected to the arms 28' and 29' of the rocking shaft 26.

A notched sector and catch may be employed to hold the lever 26 at different positions if desired, but this is not at present intended and is not indicated in the drawings. There is the usual rudder 8 and this may be operated by means of a lever, not shown in the drawing, in the usual way or 60 by means of the elevation control lever 65

which may be made to turn laterally as well as forward and rearward. When ailerons or warped sections are employed they may be operated by two pedal levers in the known way.

In machines with more than one pair of fixed wings forming the main supporting planes, these pairs are in odd numbers and the number of pairs of controlling planes is preferably increased. The next type of machine to that illustrated in Figs. 1, 2 and 3, is that in which there are three pairs of main supporting planes and four pairs preferably, of control planes. The central pair of wings is preferably set in the same plane and the pair or pairs fore and aft of the central planes are set with positive dihedral angles as hereinafter described. The central supporting planes have the greatest span and the extreme pairs of control planes the least. The intermediate planes of both kinds have a span within a straight line drawn between the extremities of the end control planes and the central plane. Respecting the dihedral angles of all the planes fore and aft of the central plane in a machine a hundred feet in length, assuming the normal dihedral angles of each end pair of control planes is 15° , the normal dihedral angles of the intermediate control planes would preferably be less. For instance that pair on each side of the central pair might have an angle of a few degrees say 5° , and the next pair 10° , and if there were another pair of wings added on each side of the central pair, the angles of all the pairs would be graduated from the central pair.

Reference will now be made to Figs. 4, 5, 10 and 11. The machine herein represented is of a larger type suitable say for military purposes. It has six fixed wings forming the main supporting planes and four pairs of controlling planes, two pairs at each end. The central main supporting planes are represented by 35 and 35', and both lie in one horizontal plane. There are two pairs of fixed planes 36 and 36' on one side and 37 and 37' on the other side of the central planes, and there are two pairs of angularly adjustable control planes forward and two pairs aft of the fixed planes. The control planes are marked 38 and 38', 39 and 39', 40 and 40', and 41 and 41'. The end pairs of planes are set with a normal dihedral angle of say 15° and are coupled up by means of the controlling cables so that from this angle they can be moved only in opposite directions, that is to say, if the angles of the fore planes 38, 38' and 39 and 39' are increased those of the aft planes 40, 40' and 41, 41' are simultaneously decreased. Each pair may be elevated and depressed from the minimum to the maximum and vice versa. Now the normal angles of 125 130

the inner pairs of control planes 38, 38' and 40, 40' are less than the normal angles of the extreme fore and aft planes. In the drawing they are set with a normal angle of 10°, their lift is 20° and they can be depressed to the horizontal only. The fixed planes 36, 37 and 36', 37' are also set with a dihedral angle of 5°. Whatever is the number of planes, both fixed and control planes, on each side of the central planes the dihedral angles of any pair would preferably be less than that of the normal of the end control planes. The control planes are all braced together in pairs in a similar manner to that described with reference to the machine with three pairs of wings just described and the bracing means will not be again referred to. All the control planes are also varied simultaneously in a similar manner. Fig. 10 represents a cross section of the body and pylon at y, y, of Fig. 5. In this view, only the control cable arrangement is shown. For each pair of control planes, the connections of the cables thereto are exactly the same as described with reference to Figs. 1, 2 and 3. For the four pairs of planes there are sixteen control cables eight connecting the extreme end pairs of planes with the rocking shaft and eight connecting the next to the end pairs of planes with said rocking shaft. In Fig. 10, only the planes 40 and 40' are seen in section looking from the central planes but the cables leading to the planes 41 and 41' are seen. The view from the central plane forward to a section through the body across the second pair of control planes would be practically the same, the only difference being that the back edges of the planes would be seen in front instead of the front edges.

A modified form of controlling arrangement is shown in Fig. 11 and may be used in a large machine such as that represented in Figs. 4 and 5. The rocking shaft 26 is moved by a hand wheel 25 to which is fixed a chain sprocket wheel 25'. A similar sprocket wheel 25'' is fixed on the rocking shaft and these two sprocket wheels are geared together with the chain band represented by 25''. The arms on the rocking shaft are similar in position to those shown in Figs. 8 and 9 but there are double the number, that is to say, there are four upper arms and four lower arms. Only the two outer arms are seen and these are indicated by 28 and 28'.

For the extreme end control planes the four upper cables are 42, 43 and 42', 43', and the four lower ones 44, 45 and 44', 45'. For the two pairs of intermediate control planes, the four upper cables are 46, 47 and 46', 47', and the four lower ones are 48, 49 and 48', 49'. The cables 45' and 49' are not seen in the drawing. The cables

45 and 49 are only seen in Fig. 10. These cables are each joined at one end to one or other of the control planes on the one hand, and at the other end to one or other of the arms on the rocking shaft on the other hand in the manner described with reference to Figs. 1, 2 and 3 of the drawings. The pylons for the control planes are marked p, p', p'' and p'''. The pulleys for the four upper cables seen in Fig. 10 are marked 50 and those for the lower cables 51.

By means of the hand wheel 25, the whole of the control planes can be simultaneously varied, the forward pairs of planes being elevated while the after pairs of planes are depressed and vice versa.

This machine is provided with two tractor screws 7 and 7'. The rudder is represented by 8. The controlling gear for the rudder is not illustrated, but the rudder may be operated by means of a hand lever, conveniently situated, and connected therewith by means of levers and cables, in the known way. The motor plant is situated forward of the central pair of planes, in the body and drives the screws by means of chain bands. In this machine, wells 6, 6' and 6'' are provided for three persons, that marked 6 being for the pilot. This machine is mounted on a chassis 2 provided with eight wheels, but no springing arrangements are illustrated. Balancing flaps or ailerons may be employed in the usual way on the central fixed planes, but none are shown in the drawings.

It must be understood, that all the planes both the control planes and the fixed planes are supporting planes. The control planes in any position, unlike the ordinary laterally pivoted control planes, are efficient supporting planes, always having the same angle of incidence.

When the machine is on the ground preparatory to starting on a flight, the extreme forward pair of control planes is brought into the horizontal plane and the extreme aft pair is raised to their maximum height of 30°, the normal dihedral angle being 15°. When the machine is up, in order to glide horizontally, the control planes are brought to their normal angle. The tendency in flight is for the control planes to assume the normal angle which is the same fore and aft. In order to descend at the maximum angle the extreme forward pair or pairs of control planes is or are elevated to their maximum which is 30° and the extreme after pair or pairs of planes is or are depressed to the horizontal plane of the machine. This produces a safe gliding angle downward. If the normal dihedral angle is more than 15°, say 25°, of course the angle of inclination of the machine both in ascending and descending is greater, namely 50°. This will not be so safe in the

shorter machines but in larger machines with of course greater supporting area, it might not be disadvantageous in cases where great risks are taken as in military machines.

5 All the pairs of control planes can be arranged to be depressed as stated to the horizontal plane of the machine but their maximum elevations depend upon their positions in accordance with the method of setting as hereinbefore explained.

10 This system of control is very sensitive as one end of the machine is elevated or receives greater support on the air at the same time as the other end is depressed through receiving less support on the air. Further, in the event of the controlling gear not being attended to, the tendency would be for the machine to glide horizontally and 15 if the control lever or its equivalent should be moved suddenly to its maximum extent say in the direction for descending, the angle of descent would be a safe one. The control planes offer no increased resistance 20 at constant speeds.

25 It is obvious that with the arrangement of bracing and control cables described, if one bracing cable of any pair of planes or one control cable were broken, the planes could be operated just the same.

30 No ailerons or warping arrangements are shown in the drawings as their application is well understood.

I claim:—

35 1. In aeroplanes, the combination with a fixed main supporting plane area, of laterally extending control planes in pairs forward and aft of said main supporting plane area, each of said control planes being pivotally attached to the body framework with the axis of rotation longitudinal, and means to support said control planes and to vary their angle simultaneously so that when 40 said forward control planes are elevated said after control planes are depressed and vice versa.

45 2. In aeroplanes, the combination with fixed main supporting plane areas, of laterally extending control planes in pairs forward and aft of said main supporting plane areas, each of said control planes being pivotally attached to the body framework with the axis longitudinal, and means to support said control planes and to vary 50 their angles simultaneously so that when said forward control planes are elevated, said after control planes are depressed and vice versa.

55 3. In aeroplanes, the combination with a fixed main supporting plane area comprising two wings, of a pair of laterally extending control planes forward of said main supporting plane area and a pair of similar control planes aft of said main supporting 60 plane area, each pair of said control planes

being pivotally attached to the body framework with the axis longitudinal, all the control planes having the same angle of incidence as that of the main supporting plane area and a normal positive dihedral 70 angle of from 15° to 25° and means for supporting said control planes, and for simultaneously varying the angles of each pair in opposite directions so that when the front pair is elevated the after pair is 75 depressed and vice versa.

4. In aeroplanes, the combination with fixed main supporting plane areas comprising wings in an uneven number of pairs, of two pairs of laterally extending control 80 planes forward of said fixed supporting plane areas and two pairs of laterally extending control planes aft of said fixed supporting plane areas, each pair of said control planes being pivotally attached to the body framework with the axis longitudinal, all the control planes having the same angle of incidence as that of the main supporting plane areas, said control planes being normally supported with a positive dihedral 85 angle of a few degrees, and means for varying said angles from the horizontal plane to the maximum angles provided for in such a manner that when the front pairs of control 90 planes are elevated, the after pairs are correspondingly depressed and vice versa. 95

5. In aeroplanes, the combination with fixed main supporting planes of laterally extending control planes forward and aft of said main supporting planes, said control 100 planes being pivotally secured to the body framework in pairs with the axis longitudinal in each case, each pair of said control planes being supported so that each one of the pair rises and falls from and to the horizontal plane uniformly with the other and the forward and after control planes being connected with an intermediate control device so that when the forward control planes are elevated, the after control planes are 105 depressed and vice versa. 110

6. In aeroplanes, the combination with fixed main supporting planes of laterally extending control planes in pairs forward and aft of said main supporting planes, said control planes being pivotally secured to the body framework in pairs with the axis of rotation longitudinal in each case, each pair of said control planes being supported by crossed bracing wire cables in pairs each 115 cable being connected to the upper surface of one control plane of the pair and passed over a pulley in a central pylon and directed downward and around another pulley and then directed upward to the under surface 120 of the other control plane of the pair so that the two said planes move uniformly upward and downward, and each control plane being raised and lowered by a pair of cables 125 guided around pulleys in the body and 130

pylons and connected respectively to the upper and lower surfaces at one end of each cable the other end of each cable being connected at diametrically opposite points to 5 arms fixed on a rocking shaft actuated by the pilot through a hand lever so that when the shaft is turned in one direction, the control planes forward of the main supporting planes are raised and those aft of said main 10 supporting planes are depressed and when turned in the opposite direction, the said forward planes are depressed and the after control planes are elevated.

7. In aeroplanes, the combination with 15 fixed main supporting planes of laterally extending control planes in pairs forward and aft of said main supporting planes, said control planes being pivotally secured to the body frame work in pairs with the axis longitudinal in each case, bracing means for supporting said control planes so that those 20 of each pair can move together uniformly up and down, an actuating lever handle fixed to a laterally arranged shaft having 25 two pairs of diametrically opposite arms thereon for each pair of forward and corresponding rear control planes and two wire cables guided over pulleys and connected respectively 30 to the upper and lower surfaces of each of said forward and corresponding after control planes and with said diametrically opposite arms so that as the shaft is turned in one direction with the hand lever, the forward pair or pairs of control planes 35 is or are raised and the after pair or pairs is or are correspondingly depressed and vice versa.

8. In aeroplanes, the combination with

fixed main supporting planes of laterally extending control planes in pairs forward and 40 aft of said main supporting planes, said control planes being pivotally secured to the body frame work with the axis longitudinal in each case, the planes of each pair being supported from a pylon by means of crossed 45 bracing cables in pairs one end of each cable of one pair being fixed to the upper surface of one plane of the pair on one side and the other end of each said cable to the underside of the other plane of the pair on the other 50 side, the cables being guided around pulleys in the pylon and body framework, and the control planes being all simultaneously elevated and depressed by means of two cables 55 to each control plane one of said cables being secured between the two said bracing cables to the upper surface of one control plane of the pair and the other cable to the under surface of the same plane in the same manner, the other ends of said two cables 60 being connected to radial arms fixed to a transverse rocking shaft provided with a lever handle, at diametrically opposite points, the control cables of the corresponding pair of planes at the opposite end of the 65 machine being similarly connected to the said radial arms, so that when the lever is moved in one direction, the control planes at one end of the machine are elevated and those at the other end are depressed and vice 70 versa.

WILLIAM MORTON JAMES.
